INTERRUPTER

Elmer E. Frey, Los Angeles, Calif., assignor to
Kittle Manufacturing Co., Los Angeles, Calif.,
a corporation of California

Application February 6, 1933. Serial No. 655,419

4 Claims. (Cl. 172—126)

This invention relates to electric interrupters, and particularly to magnetically operated contact devices for momentarily flashing electric lamps at predetermined intervals.

5 It is common practice to illuminate certain street traffic signals, such as "stop" signs, so that they will display a warning to traffic at night as well as during the day. Various types of electric lamps have been used for this purpose, and in 10 many instances electrically operated flashers have been employed to flash the lamp to make it more effective as a warning signal.

Such signs have usually been energized from commercial circuits under which conditions it 15 was not essential that the lamp and interrupter be extremely economical of current, because of the relatively low cost of energy supplied from commercial power circuits.

To avoid the expense of connecting traffic signals to commercial power mains which usually 20 involves the installation of underground wires, traffic signals having self-contained batteries for energizing the lamp have come into use. These signals usually utilize gaseous discharge lamps 25 of the neon type which are periodically flashed by momentarily applying current from the battery to the primary winding of a step-up transformer, the secondary winding of which is connected across the lamp terminals. Gaseous dis- 30 charge lamps of the type described, although requiring a high potential, use very little current, and the total energy required for the lamp is so small that it is comparable in magnitude to that required to operate the interrupter for flash- 35 ing the lamp. The over-all efficiency of a battery-operated signal, therefore, depends very largely on the efficiency of the interrupter used.

An object of the present invention is to provide 40 an interrupter that requires very little energy for its operation.

Another object of the invention is to provide an interrupter that is reliable in operation and will continue to operate for long periods without attention.

45 Still another object of the invention is to provide an interrupter that is inexpensive to manufacture.

A feature of the invention is an interrupter so 50 designed that it can be conveniently mounted in a tubular column for supporting a traffic signal.

Another feature of the invention is an interrupter having few parts and the moving parts of which are not subject to excessive wear in opera- 55 tion.

Other objects and features of the invention will

be apparent from the following detailed description, which refers to the drawing.

In the drawing:

Figure 1 is a front elevation view of an interrupter in accordance with the invention; and 60

Figure 2 is a side elevation view of the same interrupter.

The interrupter and transformer assembly herein described is adapted for insertion in the tubular supporting column of a traffic signal and 65 is therefore disclosed as supported from the top of a column 1 which has been broken away to disclose the interrupter construction.

My unit comprises a transformer mounted in a tubular transformer case 2, which, as already 70 indicated, is supported from the top of the column 1 by an outwardly extending flange 3 at the top of the transformer case. The upper end of the transformer case 2 is inset as shown and is provided with a center plate 4 and an annular 75 ring 5 extending therearound for forming the connection between the secondary winding of the transformer and a neon lamp. Thus the head containing the lamp rests upon the upper end of the column 1 and is provided with downwardly depending brushes which contact with the plate 4 and the ring 5 to complete the connections from the transformer to the lamp.

The interrupter proper, which constitutes the 80 invention, comprises a supporting panel 6 which 85 may be molded from any desired insulating material having the requisite mechanical strength and has horizontally extending flanges 7 and 8 at the top and bottom, respectively. The top flange 7 is provided for the purpose of attaching the 90 panel 6 to the lower end of the transformer housing 2. Thus I have shown the flange 7 secured to the transformer casing by screws 9.

The circuit-making and breaking elements 95 proper of my interrupter comprise a stationary contact 10 and a movable contact 11. The stationary contact 10 is mounted upon the end of an adjusting screw 12 threaded into a supporting member 13 secured to the base plate 6. A set-screw 14 is provided to clamp the adjusting 100 screw 12 against further rotation after it has been properly adjusted.

The movable contact 11 is mounted upon one end of a flexible spring supporting strip 15, the other end of which is secured, as by a screw 16, 105 or by welding or soldering, if desired, to an armature 17 which extends vertically and is pivotally mounted to the base-plate 6 at its lower end by a pivot screw 18. The strip 15 is secured to the armature 17 very close to its pivot point, as 110

shown. A delicate spring 19 connects the armature 17 to a metal plate 20 (upon which the pivot screw 18 is mounted) for insuring a good electrical connection between armature 17 and the plate 20. A binding post 21 is also provided on the plate 20 to facilitate making external electrical connection thereto from the battery which operates the interrupter.

In operation, the armature 17 is vibrated at a desired slow rate to make and break electrical connection between contacts 10 and 11 by means of an electro-magnet 22 and an oscillatable member 23.

Thus the oscillatable member 23 preferably comprises a disc having a shaft 24; the ends of which are supported in a rear pivot bearing 25 and a front pivot bearing 26, these pivot bearings being supported in fixed position by a U-shaped supporting arm 27 secured to the panel 6. The rear bearing 25 may comprise simply a hole drilled in the rear arm of the member 27 and the front bearing 26 comprises a screw having a depression in the inner end thereof to receive the shaft 24. The front bearing screw 26 can be adjusted in or out by turning it in the arm 27, it being threaded into this arm, and locking it in desired position with a locknut 28. Disc 23 is provided with a pin 29 projecting forwardly from the front face for engagement with the upper end of the armature 17 and is provided with a stop-pin 30, which is shown as a screw, positioned substantially opposite the pin 29. Pin 29 is slightly heavier than the stop-screw 30 so that in its normal position of rest the disc 23 assumes a position in which the pin 29 is in lowermost position either in contact with or closely adjacent to the armature 17.

To limit the arc of oscillation of the disc 23 and prevent excessive motion thereof, a stop spring 31, which is spiral in shape, is secured at its inner end to the bearing supporting member 27, and has its outer end positioned to intercept the stop screw 30 when the disc 23 has operated through a desired angle, approximately 90°, in a counterclockwise direction from its normal position of rest (the position shown in Fig. 1).

The armature 17 is so positioned that its weight normally maintains it in the position shown in Fig. 1, in which it is substantially in contact with the pole piece of the electromagnet 22. If desired, the connecting spring 19 may be designed to also exert a slight restraining force tending to hold the armature against the pole of the electromagnet. In this position the contacts 10 and 11 are separated so that the electrical circuit through the electromagnet to the primary winding of the transformer 2 is open. This circuit extends from the binding post 21, previously referred to, to a second binding post 32, as follows: The binding post 21 is connected through the spring conductor 19 to the armature 17 and thence through the spring contact supporting strip 15 to the movable contact 11. The fixed contact 10 is in turn connected through its supporting bracket 13 and a lead which extends back of the panel 6, to a binding post 33 connected with a wire 34 leading to one end of the primary winding of the transformer within the case 2. The other end of the primary winding of the transformer is connected by a wire 35 to a binding post 36 which in turn is connected by a wire 37, extending back of the panel 6 through the winding of the electromagnet 22 to the binding post 32, previously referred to. A battery for op-

erating the device is connected across the binding posts 21 and 32, and is shown schematically at 38.

To reduce sparking between the contacts 10 and 11, resulting from the inductive reactance of the primary winding of the transformer connected in series therewith, a condenser 39 is preferably connected across the binding posts 33 and 36. In the model shown in the drawing, this condenser 39 is of a conventional tubular type and is supported in position by clips secured to the ends thereof which are clamped beneath the binding posts 33 and 36, the clips serving to both physically support the condenser and to form the electrical connections thereto.

The device operates as follows:

Since, as previously stated, the armature 17 in its normal position of rest lies adjacent the pole piece of the electromagnet 22 in which position the contacts 10 and 11 are separated, the device is in stable equilibrium, and is therefore not self-starting. It is started by initially rotating the disc 23 a short distance in a counterclockwise direction and releasing it. As a result of the fact that the pin 29 is heavier than the stop-screw 30, the disc, when released, is in an unbalanced condition and rotates in a clockwise direction. Since the disc is very freely supported in the pivot bearings 25 and 26, it accelerates its motion until the pin 29 strikes the upper end of the armature 17 and carries the latter away from the pole piece of the electromagnet 22 a sufficient distance to bring the movable contact 11 against the fixed contact 10. This closes the electrical circuit previously traced from the battery 38 through the primary winding of the transformer within the case 2 and through the winding of the electromagnet 22. The electromagnet 22 is thereupon energized and immediately attracts the armature 17, causing it to move sharply to the right against the pole piece of the magnet 22 and simultaneously imparting an impulse to the disc 23 through pin 29, causing the disc 23 to swing in a counterclockwise direction.

The winding of the electromagnet 22 is so designed that when the battery 38 is at full strength, (as immediately after a new battery has been installed), the disc 23 is swung approximately far enough to bring the stop screw 30 into contact with the spring member 31 which serves to limit the motion of the disc and prevent it going all the way around.

Obviously if the disc oscillated through more than half a revolution it would tend to come to rest with the pin 29 against the rear side of armature 17 and would be inoperative.

Of course as soon as the electromagnet 22 has been energized and attracts the armature 17, it opens the contacts 10 and 11, thus breaking the electrical circuit, which is the desired function of the device. The armature 17, however, will remain in its forward position against the pole piece of the electromagnet 22, because that is its position of stable equilibrium, until the disc completes its oscillation in a counterclockwise direction, reverses its swing, and again brings the pin 29 into contact with the armature 17 to move it away from the magnet, close the contact 11 on the contact 10, and thereby excite the electromagnet 22 to attract the armature 17 and impart a new impulse to the disc 23.

It is therefore apparent that after being once set in operation the device will function continuously until the battery 38 becomes too weak.

to energize the electromagnet 22 sufficiently to swing the disc 23.

The device described has been found to be extremely economical of current. This is due primarily to the fact that the contacts 10 and 11 are closed only momentarily during each cycle of oscillation, the period during which they remain closed being substantially not longer than that necessary to properly excite the transformer. On the other hand, the time elapsing between successive closures of the movable contact 11 on the fixed contact 10 is relatively long because of the time required for the disc 23 to complete its swing in a counterclockwise direction, in response to an impulse transmitted to the pin 29 by the armature 17, and then reverse its direction of movement and again impact the pin 29 against the armature 17. This period, of course, may be varied between wide limits by varying the relative weights of the pin 29 and stop-screw 30 or by adding other weights to the disc at different points thereon. To facilitate the addition of other weights for changing the period of oscillation of the disc, it may be drilled at intervals about the periphery, as shown at 40.

The interrupter described is particularly designed for minimum current consumption, and it is for that reason the disc 23 is preferably so balanced that when it is at least the pin 29 barely rests against the armature 17 and does not exert sufficient force against the armature to close the contacts 10 and 11. It is to be understood, however, that by increasing slightly the weight on the right side of the disc it may be made to exert sufficient force, when at rest, against the armature 17 to close the contacts 10 and 11, in which case the device will start automatically in response to closure of the current supply circuit. With the latter adjustment, of course, more energy is required to rotate the disc in counterclockwise direction, and, therefore, the current required for operation is greater.

The device is particularly reliable and positive in operation because of the fact that the armature 17 is moved to close the movable contact 11 against the fixed contact 10 by impact of the pin 29 against the upper end of the armature. The armature itself is relatively light in weight so that when the pin 29 strikes it, it moves to the left very readily and forces the contact 11 into firm engagement with the contact 10. Furthermore, the spring contact supporting strip 15 yields slightly in response to forward movement of the armature 17 after the contacts have closed, thus producing a sliding, lateral motion of the contact 11 against the contact 10, which sliding or wiping motion has a cleaning effect upon the contact surfaces.

Experiments have shown that a dry battery comprising twelve standard cells will operate a neon lamp traffic signal for approximately a year when the circuit is interrupted with the device described. Furthermore, the interrupter requires no maintenance of any sort during

this period and is, therefore, very cheap to operate.

Having duly described the preferred embodiment of this invention, it is to be understood that I do not limit myself to the exact construction herein set forth, which may obviously be varied in detail without departing from the spirit of this invention, but only as set forth in the appended claims.

I claim:

1. An electrical interrupter comprising an electromagnet, an armature pivotally mounted for movement toward and away from said magnet, a back contact cooperating with said armature to close an energizing circuit for said magnet when the armature is moved a predetermined distance away from said magnet, said armature in its normal position of rest being toward said magnet and away from its back contact, an oscillatable member positioned to impinge against said armature near one end of its path of oscillation to deflect said armature away from said magnet and against said back contact, thereby energizing said magnet to attract said armature away from the back contact and at the same time impart an impulse to the oscillatable member to maintain it in oscillation.

2. An electrical interrupter as described in claim 1 with a resilient stop member positioned to contact with said oscillatable member at the opposite end of its path of oscillation to limit the arc of oscillation of said member.

3. An electrical interrupter as described in claim 1, in which said oscillatable member comprises a disc pivotally mounted to oscillate in a vertical plane, said disc having a pin projecting from one face thereof for striking said armature, and means including said pin for slightly unbalancing said disc, whereby it seeks a position of equilibrium in which said pin lies close to said armature.

4. An interrupter comprising a disc having a central shaft, means for pivotally supporting said disc shaft, a pin projecting from said disc and unbalancing the disc, whereby the disc normally rests with the pin in lowermost position, an armature pivotally supported below said disc and extending substantially vertically upward into engagement with one side of said pin, an electromagnet positioned to rotate said armature toward said pin, a contact cooperating with said armature to close an energizing circuit for said electromagnet in response to movement of said armature away from said magnet, whereby initial movement of said disc in a direction carrying said pin against said armature closes said circuit and causes said electromagnet to attract the armature in the opposite direction thereby swinging said pin and disc in the opposite direction and reopening said contacts until the disc reverses its swing and the pin again impacts with said armature.
